UNITED STATES PATENT OFFICE

JOHANN WILHELM REUTHER, OF HENNEF-ON-THE-SIEG, GERMANY

PACKING DEVICE FOR AUTOMATIC SACK-WEIGHING MACHINES

Application filed April 2, 1928, Serial No. 266,778, and in Germany April 7, 1927.

In automatic weighing machines in which the material runs into sacks there are used packing devices in which the packing members act against the sides of the sack, there being generally used two such packing members between which the sack is suspended. The packing members are arranged at the same level and act either alternately or simultaneously against the sack. If the packing members strike the sack alternately, the action is quite insufficient, but even when the packing members strike the sack simultaneously it is found that the packing is not sufficient because if the members act at the same level against the sack it is scarcely possible to secure a sufficiently deep penetration of the oppositely arranged packing members, even if they are operated with considerable force. Accordingly there was effected only a comparatively slight shift of the contents of the sack between the two packing members.

According to the present invention the two packing members are arranged to engage the sack simultaneously, but at different levels, either transversely to the vertical axis of the sack or at an angle thereto. By such operation the sack or its contents is, so to speak, bent to one side. The shifting of the contents of the sack effected thereby results in particularly good packing action, which is considerably enhanced when the packing device is constructed to be double-acting, two packing members being arranged at each side of the sack, of which the upper member at one side operates simultaneously with the lower packing member at the other side of the sack, and thereupon the lower packing member at the first mentioned side operates simultaneously with the upper packing member at the other side. Thus the packing members arranged opposite each other do not operate simultaneously but alternately. The sack is therefore bent alternately to one and the other side, so that a firm packing is effected in a very short time. This bending to and fro of the sack avoids injury to the sacks and creation of dust.

To effect uniform packing irrespective of the diameter of the sack, the packing members may be adjustable or replaceable.

In the accompanying drawing, Fig. 1 is a side elevation of the device, the packing members adapted to operate on the sack being shown in neutral position.

Fig. 2 is an elevation at right angles to Fig. 1.

Fig. 3 is a similar view to Fig. 1 with the packing members in working position, and

Fig. 4 a similar view of a single-acting device.

Fig. 5 is a plan showing means for adjustment of the packing members.

In the construction shown in Figs. 1, 2 and 3 the packing device is double-acting. On one end of each of the shafts *a* and *b* is mounted a double-armed packing member *c* or *d*, and on the other end of the shaft is mounted a lever *e* or *f*. The levers *e* and *f* are connected by connecting rods *k* and *l* with a crank *i* fixed to the shaft *g* which may be thrown into gear by a clutch *h*. By the rotation of the shaft *g* and thus of the crank *i* the two packing members *c* and *d* are alternately pressed against the sack, that is to say, the pressing head *d*¹ of the member *d* presses against the sack near the top while the pressing head *c*¹ of the member *c* presses against the sack near the bottom, Fig. 3. In a similar manner the pressing head *d*² of the member *d* will press against the sack at a lower point when the pressing head *c*² of the member *c* impinges on the sack higher up. The sack will thus be bent, and the flour within the sack, on every rotation of the crank *i*, will be subjected to agitation and pressure, whereby the packing is effected in an extremely short time.

In Fig. 4 is shown a single-acting packing device in which the packing member *c* impinges on the sack at a low point and the packing member *d* impinges on the sack at a higher point on the opposite side.

In the construction shown in Fig. 5 the impact members *c*¹, *c*², *d*¹, *d*² are rotatably or removably and eccentrically mounted, being concaved conformably with the external shape of the sack on both sides, and can be turned about their carrier bolts *m* held in position by springs *n* pressing projections *p* into notches *o* in the arms or members *c*.

I claim:

1. In sack packing mechanism, means for alternately simultaneously exerting pressure against opposite sides of the sack at different levels whereby to effect a bending of the sack alternately in opposite directions in the successive operation of the means.
2. In sack packing mechanism, spaced packing members arranged to coact with opposite sides of a sack to be packed, and means for actuating said members to effect pressing engagement of the same with the sack simultaneously at different levels, whereby to effect a bending of the sack between the points of engagement of the members therewith.
3. In sack packing mechanism, spaced packing members arranged to coact with opposite sides of a sack to be packed, the members being mounted, between their upper and lower ends, for rocking movement and each being provided with upper and lower presser heads to engage the sack, and means for actuating said members to alternately effect simultaneous engagement of non-corresponding ones of the presser heads of the members with the respective proximate portions of the sack, whereby to effect a bending of the sack alternately in opposite directions between the points of engagement of the members therewith.

In testimony whereof I have signed my name to this specification.

JOHANN WILHELM REUTHER.
